UNITED STATES PATENT OFFICE.

FRED M. STRECKER, OF AKRON, OHIO.

METHOD AND APPARATUS FOR COATING PIPE.

Application filed May 20, 1925. Serial No. 31,727.

To all whom it may concern:

Be it known that I, FRED M. STRECKER, a citizen of the United States, and a resident of Akron, county of Summit, and State of Ohio, have invented certain new and useful Improvements in Methods and Apparatus for Coating Pipe, of which the following is a specification.

This invention relates to methods and apparatus for coating piping or tubing with materials such as asphaltum or the like which are heated to keep them in a liquid state.

The chief objects of the invention are to provide a simple dipping tank construction for coating pipe, to provide an improved means for heating the coating material to maintain it in proper condition for applying the desired coating on the pipe and to provide an improved method for coating the pipe.

The foregoing and other objects are obtained and carried out by the apparatus illustrated in the accompanying drawings and described in detail below. It is to be understood that the invention is not limited to the specific form thereof shown and described.

Of the accompanying drawings, Figure 1 is a vertical diametral section through the apparatus;

Figure 1^a is a detail of the manner of supporting the dipping tank; and

Figure 2 is a plan thereof.

Referring to the drawings, 10 is an outer shell for the tank made up of a number of sections 11, 11 sunk into the earth a distance, somewhat greater than the length of the longest pipe section to be coated, and supported at its bottom in a concrete base 10^a.

Concentrically arranged within shell 10 is a similar shell 12 of smaller diameter, the shell 12 forming the outer wall of the dipping tank proper. Shell 12 is spaced from the bottom of shell 10 and is supported by I-beam sections 13, 13. An annular plate 14 forms a closure for the upper end of the annular space between shells 11 and 12.

Within shell 12 is supported on I-beams 13 a third shell 15 forming the inner wall of the dipping tank proper. An annular bottom plate 16, resting on I-beams 13, closes the lower end of the annular dipping tank provided by shells 12 and 15, the upper end of this tank, of course, being open. Both ends of shell 15 are open.

In the space between shells 12 and 15, the coating fluid such as asphalt, indicated at 17, is supplied.

Heading downwardly into the space between outer shell 11 and shell 12 is a pipe 18 for supplying hot gases such as may be obtained from an oil burner 19 or other suitable hot gas generating device and forced into said space by a suitable blower 20.

Arranged on shell 12 and extending outwardly therefrom on different portions of its periphery are a series of vanes 21, 21 adapted to cause the current of hot gases from pipe 18 to take paths entirely about the dipping tank to uniformly heat the fluid therein.

In operation, the hot gases flow downwardly about the dipping tank, heating it and serving also to insulate it from the earth. They then travel upwardly through shell 15 serving thus to heat the liquid in the tank from the inside as well as the outside. They then escape out of the top of shell 15 to the atmosphere.

When the coating liquid is at the desired temperature, the pipe 22, which is preferably heated before dipping, is lowered into the coating tank for a sufficient period to insure an adequate coating.

It will be seen from the foregoing that simple, inexpensive apparatus and method have been provided for effectively coating pipe. It will also be apparent that the method and apparatus are adapted with suitable modification for coating other articles of cylindrical or other structural shape without sacrificing any of the benefits to be derived from the invention. Accordingly, modifications of the invention may be resorted to without departing from the spirit thereof or the scope of the appended claims.

By the term "annular" as used in the claims, other shaped tanks are included as equivalents depending upon the cross-sectional shape of the tubing or pipe to be coated.

What I claim is:

1. Apparatus for coating pipe by dipping, comprising a tank for providing an annular column of liquid, said tank being open at the top, and means for circulating hot gas downwardly about the outer side of the tank, then upwardly about the inner side of the tank.

2. Apparatus for coating pipe by dipping, comprising a tank for providing an annular

column of liquid, said tank being open at the top, and means for circulating hot gas about the outer side of the tank and also about the inner side of the tank.

5. 3. Apparatus for coating pipe by dipping, comprising a tank providing an annular column of liquid, said tank being open at the top, a second tank surrounding the first tank, and means for circulating hot gas 10 downwardly in the outer tank and upwardly about the inner side of the first tank.

4. Apparatus for coating pipe by dipping, comprising a tank providing an annular column of liquid, said tank being open at the 15 top, a second tank surrounding the first tank, and means for circulating hot gas in the outer tank and about the inside of the first tank.

5. Apparatus for coating pipe by dipping, 20 comprising a shell sunk into the earth, an annular tank within the shell and spaced from the wall and the bottom thereof, said tank being open at the top, and means for

circulating hot gas within the shell downwardly about the tank and then upwardly 25 about the inner side of the tank.

6. Apparatus for coating pipe by dipping, comprising a tank for providing an annular column of liquid, said tank being open at the top, and means for circulating hot gases 30 about the tank.

7. Apparatus for coating pipe by dipping, comprising a tank for providing an annular column of liquid, said tank being open at the top, means for directing hot gases in a path 35 downwardly and upwardly about the tank, and a device for forcing said gases along said path.

8. Apparatus for coating pipe by dipping, comprising a tank for providing an annular column of liquid, said tank having an open top and being sunk into the earth, means providing a path for hot gases downwardly and upwardly about the tank, and means for forcing hot gases along said path.

FRED M. STRECKER.
